UNITED STATES PATENT OFFICE.

CARL POLSON, OF VERMILLION, KANSAS.

END GATE.

Application filed January 23, 1925. Serial No. 4,312.

This invention relates to end gates especially designed for use on wagons, trucks, and the like.

One of the principal objects of the invention is the provision of an end gate of this character which provides a grain-tight closure for the rear of the wagon box or the like on which it is employed.

Another object resides in the provision of an end gate of this character which may be made up of sections to provide an end gate of the desired height.

A further object is the provision of an end gate which may be readily converted into a scoop board.

A still further object resides in the provision of an end gate wherein the sections may be securely and firmly held in adjusted position by means of fastening devices arranged exteriorly of the end gate so as not to lessen the capacity of the wagon box or to impair the smooth inside surface of the end gate when the same has been converted into a scoop board.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a perspective view of one embodiment of the invention,

Figure 2 is a view similar to Figure 1 but showing the parts arranged for use as a scoop board,

Figure 2^a is a fragmentary perspective view illustrating the pivotal mounting for the T-shaped angle bars of the upper section of the end gate,

Figure 3 is a view in horizontal section on the line 3—3 of Figure 1, parts being shown in elevation for the sake of illustration,

Figure 4 is a fragmentary detail view in horizontal section similar to Figure 3 but showing the lower end gate section as positioned when used alone,

Figure 5 is a view in horizontal section illustrating the means employed for pivotally mounting the T-shaped standards,

Figure 6 is a group view in perspective illustrating the means employed for securing the angle-shaped standards of the auxiliary section in position,

Figure 7 is a view in section showing a

slightly modified form of interfitting connections between the end gate and the wagon body,

Figure 8 is a view similar to Figure 7 of a still further modified form, and

Figure 9 is a view in horizontal section further illustrating the securing means shown in Figure 6.

Referring to the drawings, and more especially to Figures 1 to 3, the numeral 1 designates the bottom or bed of a wagon, and the numeral 2 designates the sides thereof. The end gate provided in accordance with the present invention comprises a lower section 3, an upper section 4 and an auxiliary top section which may be superposed on the section 4 when employed.

When the sections 3 and 4 are employed together, the section 4 is carried on the wagon body and the section 3 is carried on the section 4. In carrying out this arrangement the section 4 is provided with a pair of T-shaped standards, designated generally at 5. The standards 5 have their upper ends secured to the section 4 of the end gate with the flanges 6 of the standards overlapping the ends of the section, the flanges 7 being disposed flush up against the inner marginal faces of the section and the flanges 8 projecting inwardly of the section 4. The flanges 6 are provided adjacent their lower ends with slots 9 in which horizontal pins 10 carried by and projecting inwardly of the sides 2 of the wagon are fitted, whereby the section 4 is mounted for adjustment about the pins 10, as an axis, thereby enabling the sections 3 and 4 to be used as an end gate or as a scoop board, as will presently appear.

In order to hold the section 4 in an upright position between the sides 2 of the wagon body, a pair of links 11 are provided and are formed with hooks 12 engageable with eyes 13 provided in brackets 14 fixed on the sides of the wagon. As described, each link 11 has a hook 12 at one end and at its opposite end each link 11 is offset and formed with a head 14. A locking bar 15 has one end 16 pivotally mounted on the offset end of one of the links 11 and the other end of the locking bar is notched or bifurcated, as at 17, and is designed to be engaged with the offset end of the other link 11 and to be held from displacement off such offset end by means of the head 14 thereon. With this arrangement when the section 4 is in an upright position, as shown in Fig-

ure 1, and the links 11 have been moved into a horizontal position, wherein they extend transversely of the section 4 and in substantial parallelism with respect to each other, 5 the locking bar 15 extends obliquely between the links 11 and the links 11 and the locking bar 15 may be conveniently held in such position by means of a locking ring 18 which is engaged with the links and with the locking bar. Brackets 20 are fixed to the section 4 and are provided with slots 21 through which the links 11 extend. One such bracket 20 is provided at each end of the section 4 and when the section 4 is locked in upright 10 position as shown in Fig. 1, the inner end 22 of each slot 21 of each bracket 20 is engaged with a link 11 so as to positively hold each end of the section 4 against outward swinging movement about the pins 10.

15 The section 4 may be readily swung to the inclined position as shown in Figure 2 by disengaging the locking ring 18 from the links 11 and the locking bar 15 and also by disengaging the yoked end 17 of the locking 20 bar from the offset and headed end of its link, whereupon the links 11 swing to the position shown in Figure 2 in which position the heads 14 of the links co-act with the offset ends of the brackets 20 to support the section 4 in an inclined position.

25 The lower section 3 has angle plates 25 secured to its ends and at each end the lower section is formed with openings 26 which extend from the outer face of the section 30 in through the body thereof and out through each end thereof. The angle plates 25 have openings 27 (see Figs. 3 and 4) which register with the openings 26. Pairs of locking rods, designated at 28 and 29, are provided.

35 The locking rods are of identical construction and each has an offset end 30 designed to slidably extend through the opening 26 provided therefor. As shown in the drawings the outer ends of the rods 28 and 29 are offset and extended through the openings 26 and the inner ends of the rods are pivotally connected to a bail or U-shaped operating lever 31 fulcrumed by means of a short shaft 32 on the bracket 33 secured 40 to the central portion of the section 3. The rods 28 are oppositely disposed with respect to the rods 29 and are connected to the lever or bail 31 on the opposite side of the shaft 32 from that to which the rods 45 29 are connected. With this arrangement when the bail or operating lever 31 is swung to a position at right angles to the section 3 the rods 28 and 29 will be simultaneously drawn towards and past the center of the section 3 so as to cause the offset ends 30 of the rods to be moved to a position within the openings 27. On the other hand when the bail or operating lever 31 is swung up 50 against the section 3 as shown in the drawings, the rods 28 and 29 will be projected

beyond the openings 27 and when the section 3 is assembled with the section 4 the projecting portions of the rods 28 and 29 will pass into openings 35 provided in T-shaped standards 5, whereby the section 75 3 is carried on these standards. It is to be noted that the ends of the rods 28 and 29 project outwardly beyond the T-shaped standards and in order to accommodate these projecting ends when the sections 3 75 and 4 are used together, the sides 2 of the wagon are formed with slots 36 which are sufficiently wide to permit the projecting ends of the rods to move in an arcuate path 80 or which may be arcuate if found desirable.

It is to be noted that the angle plates 25 play a part in pivotally mounting the sections 3 and 4 on the wagon in that one flange of each angle plate has an extension 25^a which curves under the section 3 and which underlies the slots 9 and pins 10 to prevent the pins 10 from coming out of the slots especially when the sections 3 and 4 are used as a scoop board.

In order to provide a grain-tight connection between the sections 3 and 4 and the sides of the wagon, plates, designated generally at 37, are provided on the inner faces of the sides 2 and extend from the bottom 1 of the wagon up to the tops of the sides 2. 90 Each plate 37 includes an attaching portion 38 which is fastened flush up against the inner face of the side and an offset portion 39 which is designed to provide a socket 40. The flanges 8 of the standards 5 snugly 100 fit the sockets 40 when the sections 3 and 4 of the end gate are in an upright position as shown in Figures 1 and 3. This arrangement provides for an absolute grain-tight fit between the end gate and the wagon body. 105

In lieu of the arrangement just described for providing a grain-tight fit, the sides 2 of the wagon body may be reduced at their rear ends, as shown at 41, in Fig. 7, the reduced rear ends being formed by cutting 110 away the inner portion of the sides. Flat plates 42 may be used in the arrangement shown in Fig. 7 and may be fastened up against the inner face of the side of the wagon to provide in conjunction with the reduced portions 41 sockets 43, designed to receive the flanges of the T-shaped standards 5 as before. In the arrangement shown in Fig. 8, the plates 42 are located on the outsides of the wagon body and the rear ends of the sides are cut away on their outer portions, the arrangement of Figure 8 being substantially the reverse of that shown in Figure 7. 120

An auxiliary end gate section 45 may be employed along with the sections 3 and 4 and is supported on the T-shaped standards 5 by means of angle bars 46 having hooks 47 which co-act with slots 48 in the flanges 7 of the standards 5.

If the section 3 is used alone it is posi-

tioned within the wagon body just inside of the offset portions 39 of the plates 37 and this section 3 is secured in such position by projecting the offset ends 30 of the rods 28 and 29 into openings 50 and 51 provided in the attaching portions 38 of the plates 37 and the sides 2 of the wagon respectively for the purpose of providing sockets to receive the ends of the rods, as shown in Figure 4.

The end gate described has an adaptability for many and various uses and is adapted to perform effectively in any of its many uses and applications. It can be readily converted into a scoop board. Moreover, when used as an end gate it provides an absolutely grain-tight fit and it is readily released and secured in any of its adjustments.

I claim:

- 20 1. In an end gate for use with wagons having a bottom and sides, an upper section, standards carrying the upper section, means for pivotally mounting the standards at their lower ends on the sides of the wagon, adjustable means carried by the sides of the wagon and co-operable with the upper section for securing the upper section in upright position or for supporting the upper section in inclined position, a lower section, means for mounting the lower section on the standards and comprising pairs of rods mounted on the lower section, the lower section having openings receiving portions of the rods, the ends of the rods being designed to be projected beyond the ends of the lower section, the standards having openings receiving the projecting ends of the rods, and means for projecting and retracting the rods.
- 25 2. In an end gate for use with wagons having a bottom and sides, an upper end gate section, standards mounted on the wag-

on and carrying said section, a lower section mounted on the standards, and an auxiliary top section having supporting standards provided with hooks, the standards of the upper section having slots with which said hooks are co-operable.

3. In an end gate for use with wagons having sides, an upper section, T-shaped standards secured to the upper section, means for pivotally mounting the T-shaped standards on the sides of the wagon, a lower section, means for mounting the lower section on the T-shaped standards, means carried by the sides of the wagon and co-operable with the upper section for maintaining it in adjusted position, and plates fixed to the sides of the wagon and having offset portions accommodating the flanges of the T-shaped standards to provide a grain-tight fit.

4. In an end gate, a section having angle plates at its ends and having openings extending from its outer face out through its ends, pairs of rods having offset ends extended through the openings, a bracket fixed to the section, a shaft mounted on the bracket, and a bail fulcrumed on the shaft and connected with said pairs of rods.

5. In an end gate for use with wagons having sides, end gate sections having standards at their ends provided with rearwardly directed flanges flush with the ends of the sections and designed to snugly fit the inner faces of the wagon sides at the rear end of the wagon, and plates having attaching portions flatly engaging and directly secured to the sides of the wagon and having offset portions co-acting with the sides of the wagon to define sockets in which said flanges are snugly fitted to provide a grain-tight fit.

CARL POLSON.
